UNITED STATES PATENT OFFICE.

ROGER A. KAHL, OF WALLINGFORD, CONNECTICUT.

COLLAR-BUTTON.

1,378,238.

Specification of Letters Patent. Patented May 17, 1921.

Application filed September 16, 1919. Serial No. 324,160.

To all whom it may concern:

Be it known that I, ROGER A. KAHL, a citizen of the United States, and a resident of Wallingford, in the county of New Haven 5 and State of Connecticut, have invented certain new and useful Improvements in Collar-Buttons, of which the following is a specification.

My invention relates to collar buttons adapted for use at the front of the shirt-band, and a purpose of my invention is the provision of a button which will permit the ready application and removal of a collar to and from a shirt without distorting, 10 tearing or in any way injuring the button holes of the collar. Furthermore, the invention provides a button having a base relatively thin and curved to conform to the contour of the neck so that the button 15 as a whole is prevented from pivoting and will not pierce the front of the neck and cause throat irritation as in the usual form of collar button.

I will describe one form of button embodying my invention and will then point out the novel features thereof in claims.

In the accompanying drawings:

Figure 1 is a view showing the neck-band of a shirt having applied thereto one form 30 of button embodying my invention;

Fig. 2 is a horizontal sectional view, showing the button shown in Fig. 1 in applied position within the neck band of a shirt and a collar;

Fig. 3 is a detail perspective view of the button shown in the preceding views.

Similar reference characters refer to similar parts throughout the views.

Referring specifically to the drawings, the present embodiment of my invention comprises a base B upon which is formed a shank S. As shown in Figs. 2 and 3, the base B comprises a single sheet of metal substantially rectangular in formation 45 which is relatively thin and is curved longitudinally in the form of an arc so as to conform to the curvature of the neck. The shank S extends centrally from one side face of the base B and in the present instance comprises a single sheet of flat metal which is relatively thick as compared to the base B and is notched upon its opposite longitudinal edges to provide recesses 16, 50 17 and 18. As shown in Fig. 3, the recesses

17 and 18 are formed in one edge of the shank and are disposed substantially parallel to the base B. The recesses 17 and 18 coact to provide projections 19 and 20, the outer edge of the projection 20 being curved in the direction of the base B, as clearly shown in Fig. 2. The recess 16 is formed in the opposite longitudinal edge of the shank at a point opposite to the projection 19.

In the applied position of the collar button to the neck band of a shirt, as shown in Figs. 1 and 2, the inner end 21 of the neck band receives the shank S through the usual button hole so that the walls of the latter embrace the shank at a point contiguous to the base B. The outer end 22 of the neck-band receives, through its usual button hole, the adjacent portion of the shank S in such manner that the neck-band end is disposed within the recess 17. Owing to the circumferential pull which is usually exerted between the two ends of the neck-band the end 22 is securely held within the notch 17, and this in turn maintains the end 21 in snug engagement with the base B of the button.

With the collar button in applied position upon the neck-band, the recesses 16 and 18 are exposed to receive, respectively, the walls of the usual button holes of the two ends 23 and 24 of the collar. As shown in Fig. 2, the collar ends 23 and 24 are maintained within the notches 16 and 18 by virtue of the normal tendency of the collar to expand, it being particularly noted that the arrangement of the recesses is such as to cause the collar ends to be held under tension after they have been once applied to the shank.

To remove the collar ends from the button, it is obviously that this may be readily accomplished by successively pulling the collar ends toward each other so as to permit their withdrawal from the recesses. In a similar manner, the button may be removed from the neck-band.

From the foregoing description, taken in connection with the accompanying drawings, it will be manifest that in applying or removing the collar from the button or inserting or removing the button from the neck-band that these operations may be readily accomplished without in any way

distorting or tearing the button holes because the shank S is disposed longitudinally of the button holes and not transversely thereof as in the usual form of button. Furthermore, the area and curvature of the base B is such that the button after being once inserted within the neck-band is held against twisting in any direction so that it at no time pierces the neck.

10 Although I have herein shown and described only one form of collar button embodying my invention it is to be understood that various changes and modifications may be made herein without departing from the spirit of the invention, and the spirit and scope of the appended claims.

Having thus described my invention, I claim:

1. A collar button comprising a base, a flat plate-like shank formed on said base, a pair of notches formed in one edge of said shank, and a third notch formed on the opposite edge of said shank at a point between the first-mentioned notches.
2. A collar button comprising a base, and a flat shank adapted to be disposed in a horizontal plane in the applied position of the button, said shank being formed with recesses for confining the neckband and collar ends upon the shank.

ROGER A. KAHL.
